United States Patent Office

Des. 227,568
Patented July 3, 1973

227,568

FAUCET HANDLE

Ralph E. Thorp, Lafayette, Ind., assignor to
Globe Valve Corporation

Filed Feb. 4, 1972, Ser. No. 223,809

Term of patent 14 years

Int. Cl. D23—01

U.S. Cl. D23—29

FIG. 1

FIG. 2

FIG. 3

FIG. 4

FIG. 1 is a top plan view of a faucet handle showing my new design;

FIG. 2 is a side elevation view, the side opposite being a mirror image thereof;

FIG. 3 is a front elevational view thereof; and

FIG. 4 is a rear elevational view thereof.

I claim:

The ornamental design for a faucet handle, substantially as shown and described.
